UNITED STATES PATENT OFFICE

JOHN E. GARDNER, OF CHICAGO, ILLINOIS

AUTOMATIC TELEPHONE SYSTEM

Application filed July 14, 1927. Serial No. 205,677.

My invention relates in general to automatic telephone systems.

One of the objects of the present invention is to provide an improved circuit for controlling the central office switching mechanism from a subscriber's sub-station.

Another object is to provide means for controlling the central office switches by a current or potential balancing arrangement which operates to control the operation of the switching mechanism in establishing a connection more rapidly or more positively.

Another object is to provide means that is adapted to be temporarily associated with the calling line for bringing the controlling circuit on that line to a predetermined standard so that the controlling circuit of all calling lines is identical.

Another object is to associate this equalizing equipment with the calling line during the period of controlling the central office switching mechanism and then to release it and render it available for use by other lines.

Another object is to centralize the mechanism that responds to the control of the calling line which is arranged to control the switching mechanism in establishing a connection.

Further objects are to provide new and improved circuits for the connector switches, selector switches and repeaters.

There are other objects of my invention which, together with the foregoing, will be described in the detailed specification which is to follow taken in conjunction with the accompanying drawings.

In my copending application, Serial No. 190,397, filed May 11, 1927, a new type of automatic telephone system is disclosed, in which all time functions are eliminated, and in which the operation is speeded so that a connection may be set up in a fraction of the time theretofore necessary. The control of the switching mechanism in this prior case depends upon altering an electrical characteristic of the line which causes a magnetic balancing circuit, associated with the central office switching mechanism, to control the setting up of the connection. In the present application this magnetic balancing

circuit is eliminated and a current balancing circuit is employed.

In the prior application, above mentioned it was necessary to have all the lines of the telephone subscribers in any given exchange of substantially the same resistance. In the present invention it is no longer necessary that every line in a given exchange have the same resistance. No change or alteration in the telephone line is needed.

While I have shown my invention applied to an automatic telephone system, it will be obvious that the selecting principle employed is equally applicable to any selecting system such as that employed in telegraphy, supervisory control, train control, and, in fact, in any selecting system where it is necessary to control the positioning of a device.

In practicing my invention, I provide a special type of calling device at the subscriber's station, as disclosed in the prior application, above referred to. This calling device is adapted to insert resistance in the line, depending upon the digits dialled by the calling subscriber. This resistance remains in the line until the dial restores to normal, when it is withdrawn. The calling device thus alters an electrical characteristic of the line, in this case the conductance. A similar resistance is associated with the central office switching mechanism and an electrical bridge is employed for balancing one resistance against the other through the movement of the switching mechanism. When the subscriber removes his receiver, the usual automatic trunk selection or line finding takes place, by which the subscriber's line is connected to a first selector.

When the first selector trunk is seized, apparatus in the trunk circuit brings about the operation of a finder to select the trunk. The finder has repeating and equalizing equipment associated with it. This equipment tests the calling line and inserts into the controlling circuit thereof a certain amount of resistance to bring the conductance of the line to a predetermined standard, which is determined for a given exchange. When the calling device is operated, a certain amount of resistance is placed in the circuit at the sub-station, depending upon

the digit dialled, and the conductance of the line is altered. Since the calling line constitutes one leg of the Wheatstone bridge circuit with a controlling relay connected across the mid-points, the bridge is unbalanced and the controlling relay is energized to initiate the functioning of the repeater circuit. This circuit has a small switch associated with it which is automatically operated to insert resistance, step-by-step into the fourth leg of the bridge. When the conductance of the fourth leg of the bridge is equal to the conductance of the third leg the relay across the mid-points of the bridge is deenergized and the operation of the switch ceases. By the operation of the switch a resistance corresponding to the resistance inserted into the calling line by the calling device is inserted into the trunk circuit leading to the first selector. The first selector and the other selecting mechanism is operated by a Wheatstone bridge balancing circuit in a manner similar to that already described. Thus it will be seen that the control of the switching devices occur by a current or potential balancing arrangement. This control circuit is, therefore, very accurate and positive. Since the switching mechanism is operated by a local circuit and arranged so that it will 30 control the switch as fast as the switching mechanism will operate, the operation of this mechanism takes place at high speed and the connection is established in a fraction of the time necessary in other types of automatic 35 telephone systems. When the connector is operated into engagement with the called line, if the line is idle, the common mechanism which has been associated with the first selector trunk, is released and rendered available for use by another calling line.

While in the drawings the invention has been shown and described as applied to the so-called Strowger type of automatic telephone equipment, it will be understood that 45 it may be applied equally well to the so-called panel type, relay type, and, in fact, to all types of automatic telephone systems and also to other types of selecting systems.

Referring now to the drawings, comprising 50 Figs. 1 to 5, inclusive, sufficient apparatus and circuits have been shown by means of the usual conventional diagrams to enable my invention to be readily explained and understood.

55 In the drawings:—

Fig. 1 shows an automatic sub-station A, which is provided with the usual type, transmitter and receiver. The calling device D is of the special type disclosed in my copending 60 application above referred to. This calling device is adapted to operate the springs 103 and 104.

The line of the sub-station A terminates at the exchange in a line switch C, and in the 65 multiply connected bank contacts of con-

nector switches having access to the line of the sub-station A. The line switch C is of the usual rotary type having wipers 122 to 124, inclusive, each of which is adapted to engage a bank of 25 contacts. The wipers 70 are adapted to be rotated step-by-step over their contact bank by the operation of the stepping magnet 114. The usual type of switching and line relays 112 and 113 are employed. The line relay 112 is a double 75 wound relay. The line switches such as C have access to a plurality of trunk lines, such as the trunk line comprising conductors 148 to 150, inclusive, extending to the selector S Fig. 3. A trunk circuit G is interposed 80 between the selector S and the line switch C in the first selector trunk. This trunk circuit comprises relays 130 to 134, inclusive. The trunk circuit G is adapted to initiate the operation of a rotary finder switch such as F which has access to the first selector trunks. The mechanical construction of the finder switches, such as F is similar to that of the line switch C, already described. The finder switches such as F have access to 25 selector 85 trunks. The finders provide suitable trunking arrangement whereby any selector trunk may have an idle finder associated with it or adapted to select it.

An equalizing and repeating circuit J, 95 (Fig. 2) is associated with each finder, such as F. This equalizing and repeating apparatus comprises relays 200 to 207, inclusive. An equalizing switch E is associated with the equipment J and is of the 100 same mechanical construction as the line switch C, previously described, and is adapted to be rotated by the operation of the stepping magnet 207. The switch M is a small minor switch having wipers 250 and 251 adapted to engage a series of 11 bank contacts, that is, the wipers stand in engagement with their first bank contacts. This minor switch has an operating magnet 208 and a release magnet 209. The resistances 210 and 211 comprise two legs of the Wheatstone bridge controlling circuit, as will appear.

The first selectors, such as S shown in Fig. 3, have the usual Strowger type of mechanical construction having a directly controlled vertical movement and an automatic rotary trunk selecting movement. The selector switch is provided with wipers 340 to 342, inclusive. These wipers are adapted to be moved vertically by the operation of the vertical magnet 306 and are adapted to be rotated into engagement with bank contacts, such as 345 to 347, inclusive, the terminals of an idle trunk in the level selected, by a rotary magnet 305. In addition to the usual wipers 340 to 342, inclusive, the selector is provided with a vertical wiper 335. This wiper is adapted to be operated into engagement with the vertical bank contact such as 338. There is one vertical bank contact for each level of 130

the switch, and in addition there is one normal vertical bank contact with which the wiper 335 is in engagement in its normal or released position. The vertical bank contacts are connected to a resistor 337 that is similar to the resistance 106 at the sub-station A. The vertical bank contacts are connected to the resistors in such manner that the vertical bank contact standing opposite 5 the first level is connected to the resistor 337 at a point that corresponds to the connection at the second bank contact accessible to the wiper 253 in the minor switch M of the repeating and equalizing apparatus J. This 10 point of connection, may or may not, be the same as the point of the resistor 106 to which the first bank contact of the calling device D is connected. That is, it is not necessary that the vertical bank contacts of the selector 15 switches be connected corresponding to the bank contacts of the calling device at the calling sub-station. All that is necessary is that the manner in which the resistor 337 is connected to the vertical bank contacts of 20 the selector switches be the same as the manner in which the resistor 260 is connected to the bank contacts of the minor switch M. The selector switch S is adapted to be released by the operation of the release magnet 25 307. For controlling the selector switch such as S, relays, such as the relays 300 to 304, inclusive, are provided. Two resistances 308 and 309 constitute two legs of the Wheatstone bridge controlling circuit. A sensitive 30 relay 300 is bridged or connected midway between or across the bridge. The relay 301 is a quick acting release relay. Relay 302 is an interrupter relay, relay 303 is a switching relay, and relay 304 is a controlling relay. 35

40 The trunks accessible to the selector switch S may terminate in second selectors or in connectors, depending upon the size of the system. If the trunk lines terminate in second selectors and there is more than one exchange in the system, certain of these trunk lines lead to repeaters in order that two wire trunk lines may be used for interconnecting various exchanges.

In the first case, the trunk lines leading 45 from the bank contacts 345 to 347, inclusive, extend by way of conductors 348 to 350, inclusive, to the repeater R, Fig. 4. The repeater R is provided with relays 400 to 405, inclusive. The relay 404 is an electropolarized relay having an upper polarizing winding and lower low resistance winding for operating the relay. The operation of the relay 404 is such that it will not attract its armatures until the current flow of both 50 windings is in the same direction. The relay 405 is a differential control relay. The relay 403 is adapted to supply battery to the calling line. The resistances 440 and 441 constitute the two legs of the Wheatstone bridge. 55 The relay 402 is a sensitive relay connected

across the Wheatstone bridge. There is a minor switch M¹ of the usual construction having the wipers 433 and 434, each adapted to engage in their rotation in series of ten bank contacts. Each wiper has a normal bank contact with which it is engaged. The minor switch M¹ is provided with an operating magnet 406 and a release magnet 407. There is a resistor 435 connected to the various bank contacts accessible to the wiper 433 which serves to provide for variation in resistance in one leg of the Wheatstone bridge control circuit to balance the bridge when there has been a change in resistance in its third leg which includes the controlled circuit extending back to the common repeating and equalizing equipment such as J. The resistor 435 is connected to the bank contacts accessible to the wipers 433 in a manner similar to which the resistor 337 is connected to the vertical bank contacts accessible to the wipers 335 of the selector switch S. Similarly there is a resistor connected to the bank contacts accessible to the wiper 434, so that movement of this wiper may control the selecting mechanism in the distant exchange in the same manner as if the switching equipment were controlled from a calling telephone through the equalizing and receiving equipment J. 60

The trunk lines comprising the conductors 450 and 451 extending from the repeater R terminate at another exchange in an incoming selector S¹. This selector has a circuit that is similar to the selector S, just described and is of the usual Strowger vertical and rotary type. The second selector S¹ has access to the trunk lines leading to third selectors or to connectors depending upon the size of the system. Since third selectors have the same circuit as the first selector S it will 65 be assumed that the trunk line comprising conductors 470 and 472, inclusive, extend to connector switches such as H.

The connector switches, such as H, are of the usual Strowger vertical and rotary type. The connector H is provided with vertical and rotary magnets 509 and 510 and a release magnet 508. The vertical and rotary magnets are adapted to operate the wipers 555 to 558, inclusive, first in a vertical and then in a rotary direction. Connector switches H are also provided with vertical wipers such as 560. These wipers are adapted to engage a vertical bank of 10 contacts. In addition, all the connector switches have 70 an extra wiper, such as the wiper 557 for controlling the rotary movement of these switches. This wiper and associated bank contacts are identically the same as those employed and so-called rotary connectors 75 manufactured by the Automatic Electric Company of Chicago. A resistor such as 554, is connected to the vertical bank contacts in the manner shown, and to the rotary bank contacts, corresponding rotary contacts in 80

the various levels being connected together. The connector switch H is provided with relays such as 500 to 507, inclusive, of the usual telephone type. The resistances 511 and 512 are associated with connector switch H and constitute two legs of the Wheatstone bridge circuit. The relay 500 is connected across the mid-portion of the bridge. The relay 501 is adapted to supply talking battery to the calling line. Relay 502 is what is known as a two-step or counting relay. When the upper winding of the relay 502 is energized only the armatures 521 and 526 are operated, but when the upper and lower windings of the relay 502 are energized all the armatures of this relay are attracted. The relay 503 is an interrupter relay. The relay 504 is the usual type of cut-off relay. The relay 505 is a back bridge relay for supplying talking battery to the called line. The relay 506 is a busy control relay. The relay 507 is a switching or cut-in relay.

The connector switch H has access to called subscriber's line, such as the line of the sub-station A¹, for the bank contacts 565 to 568, inclusive. The sub-station A¹ is similar to the sub-station A previously described. The line switch C¹ is the called subscriber's line switch and is similar to the line switch C previously described. The calling subscriber is adapted to be supplied with a busy tone from the busy machine BB in the event that the call line is busy, while the called sub-station is rung intermittently by ringing current from the ringing equipment R¹. These devices are of the usual type and need not be described in detail.

While in the drawings positive + and negative - signs have been used to indicate the battery connection, which may or may not be connected to ground, while - indicates the usual negative battery connection. A common battery is employed for each exchange. A booster battery may be connected in series with the main battery for the control of the common equalizing and repeating equipment such as J of Fig. 2 in the event that one is needed or desired. This connection is totally unnecessary in connection with any of the other switching mechanisms, as will appear more fully hereinafter.

Referring now to the drawings, a detail description of the operation of my improved telephone system will be given. For this purpose, it will be assumed that the subscriber at sub-station A desires to call the subscriber at sub-station A¹. In order to accomplish this result he will remove his receiver from the switch hook and operate his calling device D in accordance with the digits of the called subscriber's number. When the receiver is removed at sub-station A there is a circuit completed that extends from ground by way of back contact and armature 118, line conductor 110, transmitter 105 of sub-station A,

springs 103, switch hook springs, line conductor 111, armature 115 and its back contact and upper winding of line relay 113 to battery. The line relay 113 is energized over this circuit and operates to complete a circuit at armature 120 over a path that extends from ground through the lower winding of relay 113, armature 120 and its front contact switching relay 112, back contact and armature 117, and motor magnet 114 to battery. Another result of the operation of the relay 113 is that at armature 119 there is a circuit completed that extends from the wiper 123 by way of armature 116 and its back contact, front contact and armature 119 to a point midway between the switching relay and the stepping magnet in the previously traced circuit. If the trunk line with which the wipers 122 to 124, inclusive, of the line switch C are in engagement is idle, the switching relay 112 is immediately energized in series with the motor magnet 114. Because the relay 112 is of relatively high resistance with respect to the motor magnet 114, the latter is not operated over this circuit. In the event that the wipers 122 to 124, inclusive, of the line switch C are not in engagement with the bank contacts of an idle trunk, there will be a ground potential present upon the bank contact that is engaged by the test wiper 123 and the relay 112 will be short circuited and the motor magnet 114 will operate as a buzzer to advance the switch wipers 122 to 124, inclusive, into engagement with the bank contacts associated with an idle trunk. It will be assumed that the bank contacts 125 to 127, inclusive, are the contacts of an idle trunk accessible to the line switch C. When the switch wipers are rotated into engagement with these bank contacts, the relay 112 will be energized over the circuit previously traced. The relay 112 upon operating, opens a point in the circuit of the motor magnet 114 on armature 116, places ground upon the bank contact 126 at the front contact of this armature, opens the circuit of the upper winding of the relay 113 on armatures 115 and 118, and at the front contact of these armatures extends a calling line to the trunk circuit G. It will be noted that as soon as the line relay is energized that ground is connected to the private normal conductor 121 that is multiply connected in the banks of the connector switches so as to busy the line of the sub-station A with respect to these switches. The grounding of the bank contact 126 occurs over a circuit that extends from ground through the lower winding of the line relay 113, armature 120 and its front contact, front contact and armature 116, test wiper 123, bank contact 126, normally closed springs controlled by armature 143, armature 141 and its back contact, and relay 130 to battery. The connecting of this ground to the test contact 126 renders the selected trunk line busy, so that it is not acces-

sible to the other line switches such as C through its multiples. The line relay 113 remains energized for the present maintaining its own circuit and that of the relay 112 as well as the circuit of the relay 130 in the trunk circuit G.

The relay 130 in the trunk circuit G, upon operating prepares a locking circuit for itself and armature 135, removes ground from the bank contacts such as the bank contact 167, in the banks of finder switches F which have access to the first selector trunk such as G.

Another result of the operation of the relay 130 is that at armature 137 a circuit is prepared for the relay 133. A further result of the operation of the relay 130 is that at armature 136 there is a circuit completed which extends from ground by way of armature 145 and its bank contact, armature 136 and its front contact to starter wire 172, to start an idle finder. It will be assumed that the finder switch F is the first idle finder and in this event there will be a circuit completed for the upper winding of the relay 151. The relay 151 is energized over this circuit to complete a circuit on armature 154 that extends from ground through its lower winding, by way of said armature and its front contact, switching relay 152, back contact and armature 179, and motor magnet 180 to battery. Another result of the operation of the relay 151 is that at armature 153 a short circuit is completed to shunt the relay 152. This short circuit extends to the test wiper 152 of the finder switch F. Since the first selector trunks accessible to the finder switch F have ground connected to all their test contacts except when the first selector trunk is seized, the bank contact 157 is the only one from which ground is removed by the operation of the relay such as 130. A circuit is thereby completed for the motor magnet 180, and this magnet operates as a buzzer to advance the switch wipers 162 to 166, inclusive, step-by-step until these switch wipers are brought into engagement with the bank contacts with which the trunk circuit G is connected which, in this instance is the bank contacts 167 to 171, inclusive. When the switch wipers are brought into engagement with these line contacts there is no ground potential present upon the bank contact 167, there is no circuit for the rotary magnet 180 and the switching relay 152 is energized in series with the motor magnet. The motor magnet is not operated over this circuit by reason of the relatively high resistance of the relay 152. The relay 152 upon energizing, prepares a locking circuit for itself at armature 156, connects ground to the test wiper 162 at armature 158, at armatures 157 and 159 extend the conductors of the calling line so as to complete a circuit for the relay 205 in the common equalizing and repeating equipment J and at armatures 160 and 161

connects the first selector S under the control of the repeating equipment J.

The connecting of ground to the test wiper 162 brings about the completion of a circuit which extends from ground by way of armature 294 and its back contact in the common equalizing and controlling equipment J, conductor 181, front contact and armature 158, test wiper 162, bank contact 167, front contact and armature 137 in the trunk circuit G, and relay 133 to battery. The relay 133, upon operating, completes the circuit at armature 144 or the relay 131, removes ground from the starting circuit at armature 145, completes a locking circuit for the relay 130 at the front contact of this armature, and at armature 143 opens the original energizing circuit of the relay 130 and connects direct ground to the release trunk conductor. The connection of ground to the release trunk conductor establishes a holding circuit for the switching relay 112 in the line switch C over a path that extends from ground by way of armature 147 and its back contact, front contact and armature 143, release trunk conductors, back contacts 126, wipers 123, armature 116 and its front contact, relay 112, back contact and armature 117, and stepping magnet 114 to battery. This circuit serves to short circuit the lower winding of the line relay 113. The line relay 113 is thereupon deenergized to open a point in the selector circuit on armature 120 and to open a point in the stepping circuit in the magnet 114 on armature 119.

As mentioned before, the operation of the armature 145 and the relay 133 serves to remove ground from the starting wire 172 which is extended to the next finder by the operation of the armature 155 of the relay 152 in the finder switch F. The relay 152 at armature 155 also opens the circuit of the upper winding of the line relay 151, but this relay is maintained energized to prevent the relay 152 from deenergizing over a circuit that includes its lower winding.

The relay 205 in the common repeating equipment J is energized over a circuit that extends from ground by way of the normally closed springs controlled by armature 215, relay 205, normally closed springs controlled by armature 216, conductor 174, armature 157 and its front contact, wiper 163, bank contact 168, normally closed springs controlled by armature 183, bank contact 127, wiper 124, front contact and armature 118, over the conductors of the calling line loop, armature 115 and its back contact, wiper 122, bank contact 125, normally closed springs controlled by armature 139, bank contact 169, wiper 164, armature 159 and its front contact, conductor 175, and normally closed springs controlled by armature 230 to battery.

The release relay 205 is energized over the above circuit, and, upon operating, completes a circuit for the relay 205 and armature 228, 130

completes a circuit for the lower winding of the relay 206, removes from the multiply connected bank contacts accessible to the wiper 241 in the equalizing switch E at armature 229, at the front contact of this armature connects ground to conductor 265, completes a point in the circuit for the relay 301 of the selector switch S on armature 231 and at armature 232 opens a point in the release circuit of the minor switch M. Another result of the operation of the relay 205 is that an armature 230 transfers its own circuit from direct battery to the Wheatstone bridge control circuit and at the front contact of the armature 230 connects direct battery to the mid-point between the resistors 210 and 211 of the Wheatstone bridge control circuit. The circuit for the relay 205 extends through the resistor 210 and armature 230 and its front contact to battery. The resistors 210 and 211 comprise two legs of the Wheatstone bridge. The third leg comprises the subscriber's line circuit including the relay 205. The fourth leg of the Wheatstone bridge extends from the junction 266 of the resistor 211, wiper 242, bank contact with which said wiper is in engagement, resistor 269, normally closed springs controlled by armature 221, to ground by way of front contact and armature 229. In order that the bridge may be balanced it is necessary that the conductance of a circuit including the calling subscriber's line loop be proportional to conductance including the wipers 242 and its associated bank contacts. The value of the proportion is controlled by the proportion of the resistors 210 and 211 of the first and second leg of the bridge. In order to simplify the description, it will be assumed that the resistances 210 and 211 are exactly equal. It will, therefore, be necessary that the resistances of the third and fourth leg of the bridge be exactly equal in order that the bridge be balanced. The resistor 269 is included in the circuit of the fourth leg of the bridge to compensate for the resistance of the winding of relay 205. It will be seen that the relay 204 is connected across the bridge between the points 266 and 267. This relay takes the place of the ordinary galvanometer employed in Wheatstone bridge circuits. This relay is quite sensitive and serves to control the operation of the equalizing and repeating equipment. The sensitivity of this relay depends upon the voltage of the battery connected across the Wheatstone bridge control circuit and upon the change in conductance in the third leg of the bridge brought about for each successive setting of the calling device. If these changes in conductance are relatively large a relay of less sensitivity may be employed. The number of ampere turns and the adjustment of this relay can be very easily ascertained from calculating the changes in conductance in the third leg of the bridge and

the amount of current flow through it. That is, it is necessary that this relay remain energized until the third and fourth legs of the bridge are balanced and to then deenergize.

Since the telephone lines coming into the central office are of different lengths and sometime different characters, their conductance varies over a considerable range. Now, since the calling devices at the sub-stations are designed to alter the conductance of the lines a predetermined amount in order to control the central office switching mechanism, in order to avoid connecting the bank contacts of the calling device to their associated resistors differently on each telephone line, it is necessary to provide some means for making the conductance of all telephone lines substantially equal. In my prior application the method employed was to introduce a resistance in the line of each subscriber at the telephone exchange to bring his line up to a predetermined standard. In the present case the line equalizing and repeating equipment J is adapted to accomplish this result.

When the subscriber's line is connected to the Wheatstone bridge control circuit it has a certain amount of resistance, while the fourth leg of the bridge has very little resistance except the resistance 269, which compensates for the resistance of the winding of the relay 205. The bridge is, therefore, unbalanced and the relay 204 is energized. The result of the operation of this relay will be discussed shortly. 90 95

A resistor 270 is connected to the various bank contacts accessible to the wiper 242, which are 25 in number. The value of this resistor is equal to the resistance of the longest line coming into the exchange. A similar resistor 271 is connected to the bank contacts accessible to the wiper 243. It will be seen that any movement of the wiper 242 serves to introduce resistance into the fourth leg of the bridge. The movement of the wiper 243 serves to introduce a resistance into the third leg of the bridge including the calling subscriber's line loop after the balancing operation has been performed. 100 105 110

The operation of the relay 204 serves to open a point in the releasing circuit of the equalizing switch E at armature 227 and to complete a circuit at the front contact of this armature for the interrupter relay 203. Another result of the operation of the relay 204 is that the original circuit of the lower winding of the relay 206 is opened. When the circuit of the relay 206 is completed by the energization of the relay 205, the relay 206 merely attracts its armature 234, the other armatures 233 and 235 of the relay remaining inoperative until both the upper and lower windings of the relay 206 are energized in series. This occurs when the relay 204 is energized as described. By the operation of the relay 206 a circuit is pre-

pared for the relay 207 at armature 233 and a circuit is completed at armature 235 which extends from ground by way of armature 224 and its front contact, front contact and armature 235, armature 213 and its back contact, armature 239 and its back contact, armature 272 and its back contact, and relay 203 to battery.

The relay 201 is energized over a circuit that extends from ground by way of relay 301 in the first selector S, normally closed springs controlled by armature 327, trunk conductor 150, back contact and armature 182, bank contacts 171, wiper 166, armature 161 and its front contact, conductor 178, bank contact 253 of minor switch M, wiper 251, armature 231 and its front contact, lower winding of electropolarized relay 202, upper winding of relay 201, conductor 177, front contact and armature 160, wiper 165, bank contact 170, armature 140 and its back contact, trunk conductor 148, normally closed springs controlled by armature 322, and resistor 308 to battery. The relay 301 is energized over this circuit and, upon operating, connects ground to the release trunk conductor 149 at armature 312 over a path that extends from ground by way of armature 329 and its back contact, back contact, back contact and armature 323, off normal spring 317 and its resting contact, front contact and armature 312 to release trunk conductor 149, completes a circuit for the relay 302 at armature 313 over a path that extends from ground by way of armature 329 and its back contact, back contact and armature 323, armature 313 and its front contact, back contact and armature 328, back contact and armature 334, armature 333 and its back contact, and relay 302 to battery; opens a point in the release magnet circuit at armature 315 and at the front contact of this armature connects ground to the vertical wipers 335.

The circuit for the relay 301 including the trunk conductors 148 and 150 constitutes a third leg of the Wheatstone bridge control circuit. The fourth leg may be traced from the ground and vertical wipers 335, resistance 336 to the point 360 of the resistance 309. In order that the bridge be balanced, it is necessary that the resistance of the third leg equal the resistance of the fourth leg of the bridge. The resistance 336 in this circuit is a fixed resistance designed to compensate for the resistance of the trunk loop and for the resistance of the relay 301. The relay 300 is bridged across the Wheatstone bridge and constitutes the controlling means for the selector switch S. Since, the minor switch M in its normal position, the third and fourth legs of the bridge are in balance and the relay 300 is deenergized. The relay 302 is operated to open a point in the ground connection to the release trunk at armature 319, to establish a locking circuit for itself at

armature 320, and to complete a point in the circuit of the vertical magnet 306 at armature 321.

The connection of ground to the release trunk conductor 149 brings about the energization of the relay 134 in the trunk circuit G. The relay 134 is operated to extend the release trunk conductor 149 to the bank contacts 126 and armature 146 and to remove the ground connection through armature 147 in the trunk circuit G.

In the common repeating equipment J the relay 201 is energized in series with the relay 301 of the selector switch S. The lower winding of this relay has no effect on its operation at present time as its circuit is open. The relay 201 is energized to open one point in the release circuit of the minor switch M at armature 237 and to establish a locking circuit for the relay 206. The electropolarized relay 202 has its lower winding in series with the upper winding of the relay 201. The relay 202 is not energized because the current flow in its two windings is in opposite directions.

The relay 203 is energized to establish a locking circuit for itself at armature 224 and to complete a circuit at armature 225 that extends from ground by way of armature 229 and its front contact, armature 223 and its back contact, armature 225 and its front contact, armature 220 and its back contact, and stepping magnet 285 and the line equalizing switch E to battery. The stepping magnet 285 operates to position its pawl and to open the locking circuit of the relay 203. The relay 203 is deenergized to open a circuit of the stepping magnet 285. The stepping magnet 285 is deenergized to advance the wipers 240 to 243, inclusive, one step into engagement with their second set of bank contacts and to complete a circuit for the relay 203 at armature 272. The relay 203 and the stepping magnet 285 are alternately operated so long as the relay 203 remains energized. The operation of the wiper 242 into engagement with the second bank contact introduces a certain amount of resistance into the fourth leg of the Wheatstone bridge. The step-by-step movement of this wiper thus brings about the balancing of the bridge. That is, when the wiper 242 has introduced an amount of resistance which alters the conductivity of the fourth leg of the bridge so that the conductivity thereof is equal to the conductivity of the third leg, which includes the calling subscriber's line loop there will be no current flow through the control relay 204 and this relay will be deenergized. When the relay 204 retracts its armature 227 the circuit of the interrupter relay 203 is opened and this latter relay remains deenergized to open the circuit of the stepping magnet 285. A further result of the deenergization of the relay 204 is that at armature 227 there is a circuit com-

pleted that extends from ground by way of said armature and its back contact, bank contact with which the wiper 240 is in engagement, and said wiper, normally closed springs controlled by armature 217, and relay 200 to battery. The relay 200, upon operating, establishes a locking circuit for itself at armature 217, connects dial tone to the calling line at armature 215, introduces a resistance to alter the conductivity of the calling loop control circuit at armature 216, cuts the resistance 212 into the circuit of the fourth leg of the bridge at armature 219, opens a point in the circuit of the stepping magnet 285 at armature 220, completes a point in the circuit of the stepping magnet 208 at the front contact of this armature, and at armature 221, places the fourth leg of the Wheatstone bridge under the control of the minor switch M, as will appear. The movement of the wiper 243 serves to measure sufficient resistance to be inserted in the calling line to bring it up to a standard resistance.

The resistance 212 is a fixed resistance that is adapted to be inserted into the third leg of the bridge. This resistance has a value equal to the resistance value of the longest line in the exchange. The calling line loop is connected through the resistor 270 to the 25th bank contact accessible to the wiper 243. It will be seen that if the calling line loop is of relatively low resistance, the wiper 242 will only take a few steps, as by this movement it will have balanced the bridge. Since the resistance of the line is small it is necessary to insert a greater amount of resistance into this line than it would be if the resistance of the line was greater. This is accomplished by the connection of the calling line loop to the 25th bank contact, thus if the wiper 243 is moved only a few steps a greater amount of resistance will be inserted into the calling line upon the energization of the relay 200. In this manner the resistance of all the calling lines are brought up to a predetermined standard. Since, the fourth leg of the bridge has a fixed resistance inserted into it which balances the resistance of the calling line, the resistance of the line can be disregarded and the operation of the calling device E at the calling sub-station will bring about the same alteration of conductance in the calling line circuit on each and every line. If desirable, a booster battery may be inserted in this control circuit which includes the Wheatstone bridge and the relays 204 of a common repeating equipment. It is only necessary to insert this booster battery, if one is used, in the common equalizing and controlling equipment J.

Since the calling device D on the various telephone lines brings about the same alteration in conductance of the line for a given digit the controlling relays such as 204 in the various repeating and equalizing equipments

need no marginal adjustment, as is the usual practice. That is, in the present type of automatic telephone system working on the two wire principle, it is necessary to margin the line relay to work under varying line conditions and this is taken care of by margining the relay so that it will work between certain limits. This is done in addition to the various time margin adjustments that have to be given to the various relays with the attendant difficulties which have been explained in my prior copending application, above referred to.

Referring now to the operation of the common equalizing and repeating equipment J. After the relay 200 is energized, the circuit of the fourth leg of the bridge can be traced from the point 266 of the resistor 211, front contact and armature 219, fixed resistor 212, bank contact 252, wiper 250, armature 221 and its front contact, to ground upon trunk conductor 265. Since the resistance of the calling line is balanced by the resistance 212 the relay 204 remains deenergized. By the connection of dial tone from the dial tone machine D. T. to the calling line a signal is given to the calling subscriber that he may now operate his calling device in accordance with the digits of the called subscriber's number.

When the calling device D at sub-station A is operated in accordance with the first digit of the called subscriber's number, the wiper 100 of this calling device is positioned into engagement with a certain bank contact. When this positioning occurs the springs 104 are closed and the springs 103 are opened. In this manner the circuit of the transmitter and receiver is opened and a certain amount of resistance is placed in the calling loop circuit depending upon the position of the wiper 100. The resistance 101 serves to compensate for the resistance of the transmitter and receiver. In this manner the conductance of the calling loop circuit is altered in predetermined amount. This alteration in the conductance of the calling loop circuit, which is a third leg of the bridge unbalances the bridge and unbalances the bridge and brings about the energization of the relay 204 in the common repeating equipment J.

The relay 204 upon operating opens the original energizing circuit of the relay 200 at armature 227 and at the front contact of this armature completes a circuit which extends from ground by way of said armature and its front contact, front contact and armature 235, armature 213 and its back contact, armature 239 and its back contact, armature 272 and its back contact, and relay 203 to battery. This circuit is completed because the relay 206 is completely operated by the movement of the armature 227, removing the short circuit from the upper winding of the relay 206. The relay 203 is operated to establish

a locking circuit for itself on armature 224 and to complete a circuit at armature 225 that extends from ground upon grounded conductor 265, armature 223 and its back contact, armature 225 and its front contact, armature 220 and its front contact, and stepping magnet 208 of minor switch M to battery. The stepping magnet 208 of the minor switch M is energized to advance the switch wipers 250 and 251 one step into engagement with their first off normal set of bank contacts or their second set of bank contacts and to open the circuit of the relay 203 at armature 239. The relay 203 is deenergized to open its locking circuit at armature 224 and to open the circuit of the stepping magnet 208 at armature 225. The stepping magnet 208 is deenergized to position its pawl and to complete a circuit for the relay 203 at armature 239.

5 The movement of the wiper 250 serves to introduce a certain amount of resistance in the fourth leg of the Wheatstone bridge. The amount of resistance introduced corresponds to the amount introduced in the third leg when the wiper 100 of the calling device E is positioned in engagement with the first bank contact. The alternate operation of the relay 203 and the stepping magnet 208 continues until the switch wipers 250 and 251 10 are advanced sufficiently so that the wiper 250 has introduced an amount of resistance in the fourth leg of the bridge, so that the conductance of the fourth leg of the bridge equals the conductance of the third leg which 15 includes the calling subscriber's loop and the resistance inserted by the calling device D.

The movement of the wiper 251 of the minor switch M brings about an alteration in the conductivity of the controlling circuit 20 of the selector S, the circuit of the third leg of the Wheatstone bridge of the selector S having been traced through the wiper 251 of the minor switch M.

When the wiper 250 of the minor switch M 25 has introduced the proper amount of resistance into the circuit of the fourth leg of the bridge the wipers 250 and 251 of this switch are in a position corresponding to the position of the wiper 100 in the calling device D and the control relay 204 is deenergized to open the circuit of the relay 203 so that the movement of the switch wipers 250 and 251 ceases.

In the selector S, the conductance of the 30 third leg of the bridge controlling this selector having been altered by the operation of the wiper 251 of the minor switch M the relay 300 is energized. Upon operating, the relay 300 completes another point in the circuit for placing ground upon the release trunk conductor 149 exclusive of the off normal spring 317 at armature 310, opens a point in the circuit of the rotary magnet 305 at armature 311 and at the front contact of this 35 armature completes a circuit that extends from ground by way of said armature and its front contact, vertical magnet 306 and armature 321 and its front contact to battery. The vertical magnet 306 is operated to raise the switch shaft carrying the switch wipers 340 to 342, inclusive, opposite the first level of bank contacts and to open the locking circuit and energizing circuit of the interrupter relay 302 at armature 334. The interrupter relay 302 is deenergized to open the circuit of the vertical magnet at armature 321 and to open its locking circuit at armature 320. The vertical magnet 306 is deenergized to position its pawl and to complete a circuit for the interrupter relay 302 at armature 334. Upon the first off normal step of the switch shaft the off normal springs 316 to 318, inclusive are shifted. By the operation of the spring 316 a circuit is prepared for the release magnet 307. The operation of the spring 318 serves to prepare a circuit for the switching relay 303 while the operation of the spring 317 opens the original circuit that supplies ground to the release trunk conductor 149. However, this last operation 40 has no effect in view of the fact that ground is supplied to the release trunk conductor 149 by way of armature 310 and its front contact. By the operation of the vertical magnet the vertical wiper 335 is brought into engagement with its second bank contact. This operation serves to introduce a certain amount of resistance into the circuit of the fourth leg of the bridge. Unless this resistance is equal to the resistance inserted into the third leg of the bridge by the operation of the wiper 251 of the minor switch M, the bridge remains unbalanced and the relay 300 45 remains energized.

The circuit for the interrupter relay 302 may now be traced from ground by way of armature 329 and its back contact, back contact and armature 323, armature 313 and its front contact, back contact and armature 328, back contact and armature 334, armature 333 and its back contact, and relay 302 to battery. The relay 302 is energized to establish a locking circuit for itself and to complete the circuit of the vertical magnet. The vertical magnet 306 is operated to raise the switch wipers as before, and to open the circuit of the interrupter relay 302. The operation of the interrupter relay 302 and the vertical magnet 306 continues until the switch shaft carrying the switch wipers 340 to 342, inclusive, are brought into engagement with the proper lever of bank contacts. At this point the vertical wiper 335 will have introduced an amount of resistance into the fourth leg of the bridge corresponding to the resistance in the third leg of the bridge inserted by the operation of the wiper 252 of the minor switch S and the third and fourth leg of the bridge will be balanced. The relay 300 is thereupon deenergized to open the vertical magnet circuit 50 55 60 65 70 75 80 85 90 95 100 105 110 115 120 125 130

cuit at armature 311 and to prepare the rotary magnet circuit at the back contact of this armature. A further result of the operation of the relay 300 is that the direct ground connection through the armature 310 to the release trunk conductor 149 is open. However, ground is still connected to the release trunk conductor over a circuit that extends from ground by way of armature 329 and its back contact, back contact and armature 323, back contact and armature 319, front contact and armature 312 to the release trunk conductor 149. However, the original circuit for the interrupter relay 302 is still maintained so that this relay is energized to establish a locking circuit for itself on armature 320 and to remove the direct ground connection previously traced from the release trunk conductor 149. This operation removes the short circuit from the relay 304 which now serves to supply ground to the release trunk conductor 149 over a circuit which extends from ground by way of armature 315 and its front contact, relay 304, front contact and armature 312 to release trunk conductor 149. This circuit serves to maintain the relay 314 in the trunk circuit and the switching relay 112 in the line switch C energized, as well as to busy the first selector trunk, the relay 304 being of relatively low resistance. The relay 304, upon energizing opens a point in the original energizing circuit of the interrupter relay 302 at armatures 328 and 329, establishes a new circuit for itself at armature 330 exclusive of the front contact and armature 312 of the relay 301, prepares a point in the circuit of a relay such as 403 if the trunk lines in the level selected lead to repeaters or prepares a point in the circuit of a relay, such as 301 in the next selector, and at armature 331 completes a circuit of the rotary magnet 305. The rotary magnet 305 is energized to open the circuit of the interrupter relay 302 at armature 333 and to advance the switch wipers 340 to 342, inclusive, into engagement with the first set of contacts in the selected level.

If this trunk line is idle the switching relay 303 is energized to connect the trunk conductors 148 and 150 to the trunk conductors extending to the next switch. However, if this trunk line is busy there will be a ground potential upon the bank contacts engaged by the test wiper 341, and there will be a circuit completed that extends from this ground by way of switch wiper 341, armature 324 and its back contact, back contact and armature 334, armature 333 and its back contact, and interrupter relay 302 to battery. This circuit serves to short circuit the switching relay 303 so that it remains deenergized. The relay 302 is operated to establish a locking circuit for itself at armature 320 and to complete a circuit for the rotary magnet 305 at armature 321. The rotary magnet 305 is en-

ergized to advance the switch wipers another step and to open the circuit of the interrupter relay 302, which is deenergized to open the circuit of the rotary magnet. The alternate operation of the relay 302 and the rotary magnet 305 continues until the switch wipers 340 to 342, inclusive, are brought into engagement with the bank contacts associated with an idle trunk, which, in the present case, it will be assumed are the bank contacts 345 to 347, inclusive, to which the trunk lines comprising conductors 348 to 350, inclusive, are connected. When the switch wipers are brought into engagement with this set of bank contacts there will be no ground potential present upon the bank contact 346 engaged by the test wiper 341 and there will be no circuit completed for the interrupter relay 302. The relay 303 is thereupon energized over a circuit which extends from ground upon release 85 trunk conductor 149 working contact of off normal spring 318 and said spring, relay 303, back contact and armature 334, armature 333 and its back contact and relay 302 to battery. The relay 303 is energized over this circuit to 90 establish an alternative circuit for the relay 304 which supplies ground to the release trunk at armature 325. The relay 302 is not energized in series with the relay 303 because of the relatively high resistance of the relay 95 303. Other results of the operation of the relay 303 are that at armatures 322 and 327 the control circuit including the Wheatstone bridge and the relay 301 is opened and the trunk conductors 148 and 150 are extended to the trunk conductors 348 and 350, a point in the circuit of the release magnet is opened at armature 326 and battery is connected to wiper 342 at the front contact of this armature, and at armature 323 a point in the 100 original energizing circuit of the relay 302 is opened. The relay 301 is deenergized to open the original energizing circuit of the relay 304 at armature 315, to complete a point in the circuit of the release magnet 307 at the 110 back contact of this armature, and to open a point in the original circuit by which ground is connected to the release trunk at armature 312. A further result of the operation of relay 303 is that ground is connected to the 115 wiper 340 through the resistor 352, front contact and armature 339, armature 351 and its front contact to wiper 340. This circuit is to momentarily maintain the control circuit of the next switch inoperative until the relay 120 304 is deenergized. The resistor 352 is to compensate for the resistance of the control loop which is not included in the control circuit for the present. When the battery is connected to the wiper 342 there is a circuit completed that extends by way of this wiper, bank contact 347, trunk conductor 350, normally closed springs controlled by armature 412, upper winding of release relay 403 in repeator R, resting contact of off normal 130

spring 430 and said spring to ground. The relay 403 in the repeator R is energized over this circuit to connect direct ground to the release trunk conductor 349 at armature 420, to establish a bridge across the trunk conductor 450 and 451 at armature 422, to establish a point in its locking circuit through its lower winding at armature 423, and to open a point in the circuit of the release magnet 10 407 at armature 424.

When the relay 303 in the selector S is energized the operation of the armature 327 does not extend the trunk conductors 150 to the trunk conductor 350 until the relay 304 is deenergized. Consequently, the control circuit which constitutes the third leg of the Wheatstone bridge is opened momentarily. This operation brings about the opening of the circuit of the upper winding of the relay 201 in the common repeating equipment J. The relay 201 is deenergized to open the locking circuit of the relay 206 at armature 237 to establish a circuit for the release magnet 209 at the back contact of this armature over 25 a path that extends from ground upon grounded conductor 265, armature 237 and its back contact, and release magnet 209 to battery, and to establish a circuit for its lower winding at armature 236 over a path that extends from ground by way of back contact and armature 226, off normal spring 238 and its working contact, back contact and armature 236, and the lower winding of relay 201 to battery. This is the differential winding 30 of the relay and while it is not sufficiently powerful to operate the relay armature, it serves to maintain the relay deenergized even though the circuit for its upper winding is closed. The release magnet 209 operates to 35 bring about release of the wipers 250 and 251 of the minor switch M to their normal positions. By the movement of the wipers 250 to its normal position, a change is made in the conductance of the fourth leg of the bridge and the control relay 204 is again energized. However, the operation of the relay 204 is 40 without function at this time by reason of the fact that the deenergization at the relay 201 brought about the deenergization of the relay 206 to open the circuit of the interrupter relay 203. The relay 206 is deenergized to 45 open a point in the circuit of the interrupter relay 203 at armature 235 to open its locking circuit at armature 234 and to prepare a circuit for its lower winding at armature 233. A restoration of the wiper 251 of the minor switch M removes the resistance from the bridge across the trunk conductors 148 and 150 extending to the repeater R so that the 50 third and fourth leg of the Wheatstone bridge circuit controlling the operation of the repeater R are balanced, and the minor switch M having been released as described, the relay 402 remains deenergized.

Since the switching devices such as the

selector switch S in the central office operate under a local interrupter circuit they will operate at a very high speed as compared with the usual directive control through impulsing. This speed may be four or five times 70 as fast as the usual directive control speed. The calling device dial can thus be permitted to return to normal very rapidly. This has been explained in the copending application referred to hereintofore. It may sometimes 75 occur that the calling device dial returns to normal a great deal more rapidly than it is adjusted for, or, that a selecting device in the exchange by reason of mechanical trouble or poor adjustment will not be through operating by the time the dial restores to normal. Under these conditions unless some provision 80 were made a wrong number will be secured. In order to obviate the possibility of this I provide means associated with the common line equalizing and repeating equipment such as J for maintaining the control circuit to the switch to which the connection has been extended locked up until the switch is operated. This gives considerable additional time during 85 the pause between the separate digits dialed by the calling subscriber and until the next digit has been set up, for the equipment to operate. This provision automatically protects the system against abnormal conditions 90 such as are introduced by faulty dial construction or adjustment or faulty switch construction or adjustment. This provision will now be described.

It will be assumed that the switch wipers 100 250 and 251 of the minor switch M are in their operated position and that the selector switch S has not yet selected an idle trunk for one of the reasons mentioned when the calling device dial B at the substation A restores to normal, 105 thereby altering the conductance of the third leg of the bridge, extending to the common repeating equipment J. The positioning of the wiper 250 and the deenergization of the relay 204 bring about the completion of a circuit 110 that extends from ground by way of armature 227 and its back contact, armature 228 and its front contact, armature 233 and its front contact, and relay 207 to battery. The relay 207 is energized to establish a locking 115 circuit for itself at armature 212 to ground through the off normal spring 297 and to open the circuit of the interrupter relay 203 at armature 213. Now, when the relay 204 is again energized by the restoration of the calling 120 device dial to normal, its operation is ineffective to bring about the operation of the interrupter relay 203. Consequently, the wipers 250 and 251 of the minor switch M remain positioned until the selector switch S is operated whereupon the deenergization of the relay 201 brings about the restoration of the minor switch M to normal.

It is to be noted that the third leg of the Wheatstone bridge control circuit of the se- 125

lector switch S is unbalanced so as to initiate the operation of this switch upon the first movement of the wipers 250 and 251 of the minor switch M which is initiated by the operation of the calling subscriber's dial. 5 The above described condition wherein the calling device dial returns to normal before the operation of the selector S is an abnormal condition and one that would occur very seldom in actual practice.

10 Returning now to the description of the progress of the connecting it will be recalled that the operation of the relay 403 in the repeater R brought about the connection of direct ground to the release trunk conductor 349. This brings about the short circuiting of the ground connection through the relay 304 in the selector switch S. The relay 304 is thereupon deenergized to open a point in 15 its own circuit at armature 330 to open a point in the circuit of the rotary magnet at armature 331 and to complete the control circuit of the repeater R at armature 332.

15 The restoration of the minor switch M in the common equalizing and repeating equipment J to normal, as stated before, removes the resistance from the fourth leg of the bridge and if the dial is not yet restored to normal the operation of the relay 204 responsive to the unbalanced condition is without function since the relay 206 is deenergized to open the circuit of the relay 203.

20 Now when the calling device dial restores to normal the third and fourth legs of the Wheatstone bridge are balanced and there is no current flow through the relay 204. This relay is thereupon deenergized to complete a circuit for the lower winding of the relay 206. The relay 206 is operated to attract its 25 armature 234 thereby establishing a circuit for its upper winding which remains short circuited so long as the original circuit is maintained.

25 When the calling device is operated in accordance with the next digit the third leg of the bridge is unbalanced with respect to the fourth leg, the relay 204 is energized to open the previously traced circuit for the lower winding of the relay 206 and to prepare a 30 circuit at front contacts for the interrupter relay 203. The relay 206 is energized to open a point in the circuit of its lower winding at armature 233, to prepare a circuit for the relay 207 at the front contact of this armature 35 and to complete a circuit for the interrupter relay 203. The interrupter relay 203 is energized to establish a locking circuit for itself and to complete a circuit for the stepping magnet 208. The stepping magnet 208 operates to open the circuit of the relay 203 to advance the wipers 250 and 251 of the minor switch M one step. The relay 203 is deenergized to open the circuit of the motor magnet 208 which is deenergized to complete a circuit 40 for the interrupter relay 203. The relay 203

and the motor magnet 208 are alternately operated until the switch wipers 250 and 251 are properly positioned, that is, until these wipers have assumed a position corresponding to the setting of the calling device dial. 45 At this point the wiper 250 has inserted a sufficient amount of resistance in the fourth leg of the bridge to balance it and bring about the deenergization of the relay 204. The deenergization of the relay 204 serves to complete a circuit for the relay 207 as before and to open the circuit of the interrupter relay 203. The movement of the switch wiper 251 changes the conductance of the third leg of the bridge extending to the repeater R a 50 predetermined amount.

55 We shall now consider the effect of the operation of the minor switch M in the common repeating equipment on the repeater R. The controlling circuit to the repeater R extends from ground by way of off normal spring 430 and its resting contact, upper winding of relay 403, normally closed springs controlled by armature 412, trunk conductor 350, bank contact 347, wiper 342, normally closed springs controlled by armature 332, armature 327 and its front contact, trunk conductor 150, back contact and armature 182, bank contact 171, wiper 166, armature 161 and its front contact, conductor 178, bank 60 contact with which the wiper 251 is in engagement, said wiper, armature 231 and its front contact, lower winding of the electro polarized relay 202, upper winding of differential relay 201, conductor 177, front contact and armature 160, wiper 165, bank contact 170, armature 140 and its back contact, trunk conductor 148, front contact and armature 322, wiper 340, bank contact 345, trunk conductor 348, normally closed springs controlled by armature 413, and the resistor 440 of the first leg of the Wheatstone bridge to battery.

65 When the wiper 251 is operated by the movement of the minor switch M a certain amount of resistance is inserted into the control circuit which constitutes the third leg of the bridge and the relay 402 in the repeater R is energized. When the relay 403 in the repeater R is energized, as previously described, there is a controlling circuit completed for the incoming selector S¹ in the distant exchange. The circuit of the selector S¹ is the same as the circuit of the selector S previously described, and the relay 11: 70 in the selector S¹ similar to the relay 301 in the selector S is energized as soon as there is a bridge completed across the trunk conductors 450 and 451. This bridge may be traced from the trunk conductor 450 normally closed springs controlled by armature 410, upper winding of relay 405, normal bank contact with which the wiper 434 is in engagement, said wiper, front contact and armature 422, lower winding of electro- 11: 75 12: 80 12: 85 12: 90 12: 95 12: 100 12: 105 12: 110 12: 115 12: 120 12: 125 12: 130

polarized relay 404 to trunk conductor 451. The relay similar to 301 in the selector S^1 is operated to prepare the selector switch for operation in a manner similar to that described with respect to the selector S . In the repeater R the relay 405 is energized to prepare a circuit for the interrupter relay 401. Now, when the control relay 402 is energized, there is a circuit completed which extends from ground by way of armature 419 and its front contact, and armature 428, armature 432 and its back contact, relay 401, and normally closed springs controlled by armature 411 to battery. The relay 401 is energized over this circuit and operates to establish a locking circuit for itself at armature 416 and to complete a circuit at armature 417 which extends from ground upon release trunk conductor 349 by way of armature 414 and its back contact, armature 417 and its front contact, and stepping magnet 406 of the minor switch M^1 to battery. The stepping magnet 406 is energized to open the locking circuit of the relay 401 at armature 432 and to advance the switch wipers 433 and 434 one step into engagement with their first off normal or second set of bank contacts. The movement of the wiper 433 serves to introduce a certain amount of resistance in the circuit of the fourth leg of the bridge while the movement of the wiper 434 introduces a resistance in the previously traced control circuit for the selector S^1 . The relay 401 is deenergized since its circuit is opened by the operation of the stepping magnet 406 and this relay is deenergized to open the circuit of the stepping magnet. The stepping magnet is deenergized to complete a circuit for the relay 401. The alternate operation of the relay 401 and the stepping magnet 406 continues until the switch wipers 433 and 434 of the minor switch M^1 are properly positioned in accordance with the position of the wipers of the minor switch M in the repeating equipment J , which in turn are positioned directly from the calling subscriber's dial. When the wipers 433 and 434 of minor switch M^1 are moved into this position sufficient resistance has been introduced into the circuit of the fourth leg of the bridge to balance the bridge and bring about the de-energization of the control relay 402. This relay is deenergized to open the circuit of the interrupter relay 401 and the rotary movement of the wipers 433 and 434 ceases. Upon the first off normal step of the switch the off normal springs 430 and 431 are shifted. The operation of the off normal spring 431 serves to prepare a circuit for the lower winding of the relay 405 while the operation of the off normal spring 430 opens a point in the circuit of the lower winding of the relay 403. However, since the relay 405 is operated the armature 429 is in engagement with its front contact so that the shifting of

the off normal spring 430 is without function at the present time. The operation of the armature 429 and the relay 405 also serve to open a point in the locking circuit of the lower winding of the relay 403. The operation of the armature 427 of the relay 405 opens a point in the circuit of the release magnet 407.

The movement of the wiper 434 of the minor switch M^1 introduces a certain amount of resistance in the bridge of the trunk conductors 450 and 451 which alters the conductance of the third leg of the Wheatstone bridge controlling the operation of the selector S^1 . The amount of the alteration depends upon the amount necessary to bring about the operation of the selector S^1 to the proper position, and also the proper positioning of the other switching devices by repeated controlling circuits from the repeater R . That is to say, the movements of the wiper 434 of the minor switch introduce an amount of resistance which will be similar to the amount of resistance introduced by the common repeating equipment in the distant exchange similar to the repeating equipment J in the exchange of the line of substation A.

The selector S^1 is thereupon operated in the same manner as the selector S to position its wipers vertically opposite the proper level of bank contacts and to then select an idle trunk in the selected level. When an idle trunk line has been selected the operation of the relays in the selector S^1 , similar to the relays 303 and 304 in the selector S serve to momentarily open the control circuit extending to the repeater R . It will be assumed that the movement of the selector S^1 under the control of the repeater R has been such as to bring the wipers 455 to 457, inclusive, into engagement with the bank contacts 458 to 460, inclusive, to which the trunk lines comprising conductors 470 to 472, inclusive, are connected, extending to the connector switch H .

When the control circuit is opened the relay 405 which is maintained energized over this circuit in the repeater R is deenergized to complete a circuit for its lower differential winding at armature 426, to complete a circuit for the release magnet 407 at armature 427, to open a point in the stepping circuit at armature 428, and at armature 429 to open the controlling circuit extending back to the common repeating equipment J through the upper winding of the relay 403. However, the relay 403 is not deenergized because the locking circuit is simultaneously completed for its lower winding at the normally closed springs controlled by armature 429.

The operation of the release magnet 407 brings about the release of the wipers 433 and 434 so that the balancing and repeating circuits on the repeater R are restored to nor-

mal in order that they may be operated in accordance with the next digit.

In the common line equalizing and repeating equipment J the opening of the controlling circuit extending to the repeater R brings about the deenergization of the relay 201, which is included in this circuit. This relay is deenergized to complete a circuit for its differential winding on armature 236 to open a circuit of the relay 206 on armature 237 and to complete a circuit for the release magnet 209 at the back contact of this armature. The release magnet 209 operates to restore the wipers 250 and 251 of the minor switch M to their normal position. This operation serves to bring the wipers in position so that they may be operated in accordance with the next digit dialed by the calling subscriber. The relay 206 is deenergized to open a point in the circuit of the interrupter relay 203 at armature 235, to open a point in the circuit of the relay 207 on armature 238 and to prepare a circuit for its lower winding at the back contact of this armature. When the switch wipers 250 and 251 of the minor switch M are restored to normal, the off normal springs 297 and 238 are shifted. The operation of the off normal spring 297 opens the circuit of the relay 207 and this relay is deenergized to prepare a point in the circuit of the interrupter relay 203 at armature 213. The operation of the off normal spring 238 serves to open the circuit of the lower winding of the relay 201 so that this relay may be energized over the control circuit to the repeater R through its upper winding.

The control circuit to the repeater R is reestablished and the wipers 433 and 434 of the minor switch M¹ are restored to normal whereby the off normal springs 430 and 431 are shifted and the relay 405 energized again. This energization of the relay 405 occurs as soon as the relay 501 in the connector H, which has been selected by the operation of the selector S¹ is energized to apply ground to the release trunk conductor 471. The relay 501 in the connector switch H is energized over a circuit which extends to battery through an armature similar to the armature 326 in the selector switch S¹. The connection of ground to the release trunk conductor 471 by the operation of the armature 520 and the relay 501 brings about the deenergization of a relay similar to the relay 304 in the selector S¹ and the control circuit is established for the third leg of the Wheatstone bridge controlling circuit associated with the connector switch H. This circuit may be traced from ground by way of off normal spring 552 and its resting contact, lower winding of relay 501, normally closed springs controlled by armature 548, trunk conductor 472, bank contact 460, wiper 457, through the selector switch S¹, inter-exchange trunk con-

ductor 451, lower winding of the electro-polarized relay 404, armature 422 and its front contact, wiper 434, normal bank contact with which said wiper is in engagement, upper winding of relay 405, normally closed springs controlled by armature 410, inter-exchange trunk conductor 450, through the selector switch S¹, wiper 455, bank contact 458, trunk conductor 470, normally closed springs controlled by armature 541, resistor 511 constituting one leg of the Wheatstone bridge, armature 597 and its back contact to battery. The relay 501 is energized over this circuit and operates to prepare the Wheatstone bridge circuit at armature 598. The resistance 561, which is included in the circuit of the fourth leg of the bridge serves to compensate for the resistance of the control circuit extending back to the repeater. The relay 500 is deenergized until the repeater R is operated to alter the conductance of the third leg of the bridge. The relay 501 is also operated to prepare a locking circuit for the lower winding of the relay 507 in addition to placing ground upon the release trunk conductor 471.

In the common repeating equipment J the relay 204 is restored to normal when the calling device dial at the calling substation is restored to normal. The deenergization of the relay 204 operates to complete a circuit for the relay 206. This relay is energized to prepare a circuit for its upper winding at armature 234. When the calling device dial is operated in accordance with the next digit the relay 206 is energized, as is the relay 204 to complete a circuit for the interrupter relay 203. The interrupter relay 203 and the stepping magnet 208 operate as before alternately to bring about the positioning of the wipers 250 and 251 of the minor switch M at their proper point in accordance with the digit dialed by the calling subscriber. The positioning of the wiper 250 serves to balance the fourth leg of the bridge thereby bringing about the deenergization of the relay 204 and stopping the rotation of the switch wiper. The deenergization of the relay 204 also completes a circuit for the relay 207. The positioning of the wiper 251 brings about the insertion of a certain amount of resistance into the control circuit extending to the repeater R. This brings about energization of the relay 402 in the repeater which is energized to complete a circuit for the interrupter relay 401. The interrupter relay 401 serves to operate the stepping magnet 406 until the wipers 433 and 434 of the minor switch M¹ are properly positioned in accordance with the setting of the wipers of the minor switch M in the common repeating equipment. The movement of the switch wiper 433 serves to introduce an amount of resistance in the fourth leg of the bridge sufficient to balance the bridge and 130

to bring about the deenergization of the relay 402 which causes the cessation of the movement of the switch wipers 433 and 434. The movement of the switch wiper 434 introduces a certain amount of resistance in bridge of the trunk conductors 450 and 451 thereby altering the conductance of the control circuit which constitutes the third leg of the bridge in the repeater B extending to the armature H.

The relay 500 in the connector H is thereupon energized to complete a circuit at armature 516 that extends from ground by way of said armature and its front contact, back contact and armature 532, and relay 506 to battery. The relay 506 is energized to open a point in the locking circuit of the upper winding of the relay 501 at armature 540, to connect ground to the lower winding of relay 501 in multiple with the ground connected to its lower winding through the off normal spring 552, to complete a circuit for itself exclusive of the armature 532 of the relay 504 on armature 539, to prepare a circuit for the rotary magnet at armature 538 and to prepare a testing circuit at armature 537. Another result from the operation of the relay 500 is that at armature 515 there is a circuit complete which extends from ground by way of said armature and its front contact, back contact and armature 546, back contact and armature 529, and relay 503 to battery. The relay 503 is energized to establish a locking circuit for itself at armature 527, and to complete a circuit at armature 528 over a path which extends from ground by way of armature 528 and its front contact, armature 525 and its back contact, and vertical magnet 509 to battery. The vertical magnet 509 is energized to raise the switch shaft carrying the wipers 555 to 558, inclusive, and 560 one step. Another result of the operation of the vertical magnet 509 is that at armature 529 the circuit of the interrupter relay 503 is opened and this relay is deenergized to open the circuit of the vertical magnet, which also deenergizes. The deenergization of the vertical magnet serves to complete another circuit for the relay 503. The movement of the vertical wipers 560 into engagement with the vertical bank contact opposite the first level serves to introduce a certain amount of resistance into the circuit including the fourth leg of the bridge. If the digit 1 has been called by the calling subscriber at sub-station A this movement of the vertical wiper will serve to bring about a balance of the bridge. However, if some other digit than 1 has been dialed the interrupter relay 503 and the vertical magnet 509 are alternately operated until the switch wipers are brought opposite the proper level of bank contacts. By the operation of the vertical wiper 560 sufficient resistance has been inserted in the fourth leg of the bridge to bal-

ance it and the control relay 500 is deenergized to open the circuit of the interrupter relay 503. The retraction of armature 516 of the relay 500 opens the circuit of the relay 506 while the retraction of the armature 516 opens the circuit of the interrupting relay 503. The operation of the off normal springs 552 away from its resting contact opens the original circuit by which ground is supplied to the lower winding of the relay 501, though this operation is ineffective at the present time because the relay 506 is energized to maintain this ground connection over a path that extends from ground by way of armature 520 and its front contact, normally closed springs controlled by armature 547, normally closed springs controlled by armature 533, front contact and armature 540, to one terminal of the lower winding of the relay 501.

It will be recalled that the lower winding of the relay 501 included in the control circuit forming the third leg of the Wheatstone bridge control circuit, is supplied with ground through the armature 540 of the relay 506. Since the relay 506 is deenergized immediately upon the deenergization of the relay 500 the circuit of the relay 501 is opened. Simultaneously there is a locking circuit completed for the upper winding of the relay 501 to maintain it energized at the normally closed springs controlled by armature 540. Another result of the operation of armature 540 is that the circuit of the fourth leg of the bridge is opened by the removal of the ground from wiper 560.

The opening of the control circuit formed by the third leg of the controlling bridge in the connector H brings about the deenergization of the relay 405 in the repeater R. The relay 405 is deenergized to bring about the restoration of the wipers 433 and 434 of the minor switch M¹ to normal, as well as the opening of the Wheatstone bridge control circuit extending back to the common repeating equipment J.

The opening of the control circuit extending to the repeater J brings about the deenergization of the relay 201 which operates to release the wipers 250 and 251 of the minor switch M as well as to bring about the deenergization of the relay 206. When the calling device dial D at the calling sub-station A restores to normal a circuit is completed for the relay 206 in the common repeating equipment J. This relay is energized to prepare a circuit for the interrupter relay 203 as soon as the calling device dial is operated in accordance with the next digit.

When the calling device dial is operated in accordance with the next digit of the calling subscriber's number the control relay 204 in the common repeating equipment J is energized to bring about the alternate operation of the interrupter relay 203 and the stepping

- magnet 208 to position the wipers 250 and 251 of the minor switch S. The positioning of the wiper 250 brings about the balancing of the Wheatstone bridge control circuit extending back to the subscriber's sub-station 5 and the deenergization of the relay 204. The deenergization of the relay 204 brings about the cessation of the movement of the minor switch M and the operation of the relay 207. The position of the wiper 251 of the minor switch M alters the conductance of the control circuit extending to the repeater R a predetermined amount, thereby causing the energization of the relay 402 in the repeater. 10 The relay 402 brings about the alternate operation of the interrupter relay 401 and the stepping magnet 406 to position the wipers 433 and 434 of the minor switch M¹. The operation of the wiper 433 serves to balance 15 the bridge when the wipers are properly positioned to bring about the deenergization of the relay 402.

In the connector H, the deenergization of the relay 506 which initiated the release of the 20 minor switches M¹ and M in the repeater R and common repeating equipment J, respectively, also brings about the closure of the circuit that extends from ground by way of off normal spring 552 and its working contact, back contact and armature 554, back contact and armature 526, and upper winding of relay 502 to battery. The relay 502 is energized to attract its armature 521 thereby completing a circuit for its lower winding. 25 The circuit for its lower winding is not effective so long as the original circuit of the relay is maintained. The armature 526 is also operated to open the original energizing circuit of the relay 502 and this relay is permitted to operate through the action of its two 30 windings in series. The armature 526 is adjusted to break some time after the armature 521 makes engagement with its front contact. The resistance of the relay winding is relatively high so as to make it slow to energize. 35 The relay 502 upon operating, opens a point in the circuit of the vertical magnet 509 at armature 525, prepares a circuit for the rotary magnet at the front contact of this armature, completes a circuit for the lower winding of 40 the relay 501 at armature 523 and at armature 524 disconnects ground from the vertical wiper 560 and connects to the rotary wiper 557 and to the fourth leg of the bridge through 45 the rotary off normal spring 518 and its resting contact. The relay 502 is wound and adjusted so as to be somewhat slow to energize in order to permit the minor switch M in the repeater R to restore to normal before the relay 502 completely attracts its armature to 50 close the circuit for the third and fourth legs of the Wheatstone bridge. Since the wiper 434 is in its normal position there is no resistance in the circuit of the third leg of the 55 Wheatstone bridge and the relay 500 remains

deenergized upon the energization of the relay 502. Even though the wiper 434 of the minor switch M¹ in the repeater R is not fully restored to normal by the time the relay 502 operates the momentary energization of the relay 500 will have no particular effect. This is true because the relay 500 completes a circuit at armature 516 for the relay 506, which must be operated before the energization of the interrupter relay 503 can complete a circuit for the rotary magnet 510. The relay 506 also has a high impedance winding so that it is somewhat slow to energize. Consequently the momentary operation of the relay 500 while it may bring about the energization of the interrupter relay 503 will have no further effect because the circuit of the rotary magnet is opened at armature 538. This allows ample time for the release of the minor switch M¹ in the repeater R. 70 75 80 85 90 95 100 105 110 115 120 125 130

Returning now to the operation of the connector H responsive to the setting of the minor switch M¹ in the repeater R for the final digit of the called subscriber's number. When the conductance of the third leg of the Wheatstone bridge that controls the operation of the connector H is altered a predetermined amount, as determined by the setting of the calling subscriber's dial, the relay 500 is energized to complete a circuit at armature 515 over a path that extends from ground by way of said armature and its front contact, back contact and armature 546, back contact and armature 529 and interrupter relay 503 to battery. The interrupter relay 503 is energized to establish a locking circuit for itself at armature 527 and to complete the circuit of the rotary magnet on armature 528. Another result of the operation of relay 500 is that at armature 516 a circuit is completed that extends from ground by way of said armature and its front contact, back contact and armature 532, and relay 506 to battery. The relay 506 is energized to connect the test wiper to the lower winding of the relay 504 on armature 537, to complete a point in the circuit of the rotary magnet on armature 538, to complete a circuit for itself exclusive of the springs 532 on the relay 504, to connect ground to the third and fourth legs of the bridge at armature 540, to open a locking circuit of the upper winding of the relay 501 at the normally closed springs controlled by this armature, and to open a point in the circuit of the upper winding of the relay 502 at armature 554. The circuit for the rotary magnet extends from ground by way of armature 528 and its front contact, armature 525 and its front contact, armature 538 and its front contact, and rotary magnet 510 to battery. The rotary magnet 510 is energized to advance the switch wipers 555 to 558, inclusive, one step into engagement with their first bank contact on the level to which the switch wipers have been raised, 110 115 120 125 130

and to open the circuit of the interrupter relay 503 at armature 546. The movement of the switch shaft in a rotary direction brings about the shifting of the off normal springs 517 and 518. By the shifting of the off normal spring 517 the ground connection to the third and fourth legs of the bridge through this spring is eliminated, though ground is still connected thereto by the armature 540 of the relay 506. By the shifting of the off normal spring 518 the connection to the fourth leg of the bridge through the off normal spring 518 is open. The movement of the wiper 557 into engagement with the first rotary bank contact in the level selected inserts a certain amount of resistance into the first leg of the bridge. The relay 503 is again energized to bring about the operation of the rotary magnet 510. The relay 503 and the rotary magnet 510 are alternately operated until the switch wipers 555 and 558 are brought into engagement with the bank contacts of the called subscriber's line at substation A¹, which in this case, it will be assumed are the bank contact 565 to 568, inclusive. The movement of the wiper 557 into this position brings about the insertion of resistance into the circuit of the fourth leg of the bridge to effect a balance thereof. The relay 500 is thereupon deenergized to open the circuit of the interrupter relay 503 and to open the circuit of the relay 506.

In order to describe the operation of the connector switch H, it will first be assumed that the line of the sub-station A¹ is busy. Under these conditions there will be a ground potential present upon the bank contact 566 engaged by the test wiper 556. When the switch wipers 555 to 558, inclusive, are brought into engagement with the bank contacts 565 to 568, inclusive, the ground present upon the bank contact 566 will complete a circuit by way of the test wiper 556, armature 537 and its front contact, and the lower winding of relay 504 to battery. The relay 504 is energized over this circuit to prepare a locking circuit for itself at armature 531, to open a point in the circuit of the relay 507 at this same armature, to open a point in the circuit of the relay 506 on armature 532, to connect ground to the third and fourth legs of the bridge at armature 533 and connect the busy tone to the calling subscriber's line on armature 534. The subscriber at substation A is enabled to hear this busy tone by reason of the condenser 190 which connects the trunk conductor 150 to the conductor extending to the bank contact 127.

The calling subscriber upon hearing the busy tone will replace his receiver upon the switch hook. The replacement of the receiver at the calling sub-station opens the calling loop circuit which includes the relay 205 in the common receiving equipment J. The relay 205 is deenergized to open a point in the circuit of relay 206 at armature 228, to open the locking circuit of the relay 200 at armature 229, to connect ground to the multiply connected bank contacts accessible to the wiper 241 at the back contact of this armature, to open a point in the Wheatstone bridge control circuit at armature 230, to open the control circuit extending to the repeater R at armature 231, and to complete a circuit for the release magnet 209 of the minor switch M over a path that extends from ground by way of back contact and armature 226, off normal spring 238 and its working contact, armature 232 and its back contact, and release magnet 209 to battery. The release magnet 209 operates to restore the switch wipers 250 and 251 of the minor switch M to their normal position. The relay 200 is deenergized to restore its armature to normal. The connection of ground to the multiply connected bank contacts accessible to the wipers 241 of the line equalizing switch E completes a circuit that extends by way of the multiply connected bank contacts to the wiper 241, armature 239 and its back contact, armature 272 and its back contact, and relay 203 to battery. The relay 203 is energized to complete a circuit that extends by way of armature 224 and its front contact, armature 291 and its back contact, armature 220 and its back contact and stepping magnet 285 to battery. Stepping magnet 285 is energized to advance the switch wipers 240 to 243 one step and to open the circuit of the interrupter relay 203. The relay 203 and the stepping magnet 285 are alternately operated until the switch wipers 240 to 243, inclusive, are brought to their normal position where the circuit of the relay 203 is opened, since the first bank contact 245 accessible to the wiper 241 of the switch E is not connected in multiple with the remaining contacts. The deenergization of the relay 205 also opens the locking circuit of the relay 152 of the finder switch F. The relay 152 is deenergized to disconnect the finder switch from the first selector trunk. One of the results of the deenergization of the relay 152 is that ground is removed from the wiper 162 and the relay 133 in the trunk circuit is deenergized. The deenergization of this relay opens the circuit of the relay 130 at armature 145. The relay 130 is deenergized to open a point in the starting circuit at armature 136 and connect ground to the bank contact 167 of the finder switch S. The finder switch F is now in position to select another selector trunk when it is seized by a calling line.

The opening of the control circuit in the common repeating equipment J brings about the deenergization of the relay 403 in the repeater R. The relay 403 is deenergized to open the bridge across the trunk conductors 450 and 451 extending to the connector H.

at armature 422, to open a point in its locking circuit at armature 423, to complete a circuit for the release magnet 407 at armature 424 to remove ground from the release trunk conductor 349 at armature 420. The relay 405 is deenergized since it is in bridge of the trunk conductors 450 and 451. This relay deenergizes to restore certain circuits to normal. The release magnet 407 is operated over a circuit which extends from ground by way of back contact and armature 418, off normal spring 431 and its working contact, armature 424 and its back contact, and release magnet 407 to battery. The release magnet 407 is energized to restore the wipers 433 and 434 to their normal position. At this point the off normal springs 430 and 431 are shifted. The removal of ground from the release trunk conductor 349 brings about deenergization of the switching relay 303 in selector S, the deenergization of the relays 134, 131 and 132 in the trunk circuit G, and the deenergization of the switching relay 112 in the line switch C.

The deenergization of the switching relay 303 in the selector switch S brings about the restoration of all its armatures to normal. The movement of the armature 326 completes a circuit for the release magnet 307. The release magnet 307 operates to restore the switch shaft carrying the switch wipers 340 to 342, inclusive, and the vertical wipers 335 to its normal position. The selector switch is now restored to normal and rendered available for the next call.

The relay 134 in the trunk circuit G upon deenergizing, connects ground to the armature 143 at armature 147 and at armature 146 disconnects the release trunk conductor 149 from the conductor that extends to the bank contact 121 of the line switch C. The deenergization of the relay 131 opens a point in the circuit of the relay 132 at armature 138. The relay 132 is deenergized to restore certain circuits to normal.

In the line switch C, the relay 112, upon deenergizing, restores the battery and ground connection of the calling line conductors 111 and 110, respectively. The line switch C may now be operated for the next call. In this manner all the equipment in the exchange of the subscriber at sub-station A is released.

We shall now consider the release of the apparatus in the exchange in which the called line of the sub-station A¹ terminates. When the control circuit extending between the connector switch H and the repeater R is opened, as described, the relay 501 in this switch is deenergized. The relay 501 upon deenergizing, opens the locking circuit of the relay 504 on armature 519, removes ground from the release trunk conductor 471 at armature 520, and at armature 522 completes a circuit for the release magnet 508. The release magnet 508 is energized to restore the switch

shaft carrying the wipers 555 to 558, inclusive, and the vertical wiper 560 to its normal position. The circuit of the release magnet 508 is opened by the shifting of the off normal spring 551 when the switch shaft restores to normal. 70

The removal of ground from the release trunk conductor 471 brings about the opening of the circuit of the relay, similar to the relay 303 of the selector S, in the selector S—1. This relay is deenergized to restore the switch shaft carrying the wipers 455 to 457, inclusive, to normal. 75

In the above manner all the equipment used to establish the connection to the line of the sub-station A¹ is released upon the calling subscriber, replacing his receiver upon the switch hook after hearing the busy tone. 80

It will now be assumed that when the wipers 555 to 558, inclusive, of the connector H are rotated into engagement with the bank contact 565, to 568, inclusive, to which the line of the sub-station A¹ is connected, that this line is idle. Under these conditions, there will be no ground potential present upon the bank contact 566 engaged by the test wiper 556. Since there is no ground potential present upon the trunk contact 556 when the wipers 555 to 558, inclusive, of the connector H are brought into engagement with the bank contacts 565 to 568, inclusive, there will be no circuit completed for the lower winding of the relay 504 and this relay will not be energized. When the relay 506 is deenergized following the deenergization of the relay 500 the circuit of the lower winding of the relay 501 is opened at armature 540 and a locking circuit is established for its upper winding through the normally closed springs controlled by this armature. This operation 90 opens the control circuit back to the repeater R. This may or may not bring about the release of the minor switch M¹ in the repeater R and the minor switch M in the common repeating equipment J. The reason that this 95 operation is immaterial is that the line of the calling subscriber has been connected to the line of the called subscriber. Another result of the deenergization of the relay 506 is that there is a circuit completed which extends 100 from ground by way of armature 519 and its front contact, armature 531 and its back contact, upper winding of relay 507, back contact and armature 537, wiper 556, bank contact 556, switching relay 570 of the called line switch 105 C¹, and motor magnet 572 to battery. The switching relay 570 of the line switch C¹ is energized in series with the upper winding of the relay 507. The operation of the relay 507 in the line switch C¹ brings about the 110 attraction of its armature sufficient to disengage their back contacts, but not sufficient to engage their front contacts by reason of a mechanical interlocking device controlled by the armature of the line relay 571. 115

120

125

130

In the connector switch H the relay 507 is energized to establish a locking circuit for its lower winding at armature 544, to connect direct ground to the test wiper 556 at armature 543, to reconnect ground to the lower winding of the relay 501 at armature 547 and to open the locking circuit of the upper winding of this relay at the normally closed springs controlled by this armature, to complete the ringing circuit at armatures 549 and 542, and to reverse the current flow over the control circuit extending back to the repeater R at armatures 541 and 548. The operation of the armature 541 disconnects the Wheatstone bridge controlling circuit and connects the upper winding of the relay 501 into the circuit extending back to the repeater R. Another result of the operation of the relay 507 is that at armature 553 the battery is removed from the Wheatstone bridge so as to prevent the energization of the relay 500. The relay 501 thus supplies battery to the trunk conductors 470 and 472 and if no repeaters are used during the establishing 25 of the connection, that is, if the call is one local to the exchange the relay 501 supplies talking battery to the calling subscriber.

The reversal of current flow over the conductors 470 and 472 brings about the energization of the electropolarized relay 404 in the repeater R. The relay 404 is operated to attract its armature 425 thereby completing a circuit for the relay 400. The relay 400 upon operating, disconnects the bridge across the 35 trunk conductors through the upper winding of the relay 405 and connects the relay 401 in this circuit to raise the impedance thereof at armatures 410 and 411, to open one point in the circuit of the stepping magnet 406 at armature 414 and to connect direct ground to the relay 403 at armature 415. Another result of the operation of the relay 400 is that the current flow over the conductors 348 and 350 is reversed at armatures 412 and 413.

This reversal of current flow brings about the operation of the electropolarized relay 202 in the common repeating equipment J. The relay 202 is operated to open the locking circuit of the switching relay 152 in the finder switch S at armature 222 and to open the locking circuit of the relay 133 in the trunk circuit G at armature 294. The relay 152 upon deenergizing, opens another point in the circuit of the relay 133 at armature 158, re-connects the starting wire 172 to the upper winding of the line relay 151 at armature 155, and at armatures 157, 159, 160 and 161 disconnects the first selector trunk from the common repeating equipment J. The disconnection of the first selector trunk from the common repeating equipment J brings about the deenergization of the relay 205. The release of the common repeating equipment follows the deenergization of the relay

205 in the same manner as has been previously described.

The relay 133 in the trunk circuit G, upon deenergizing, opens the original energizing circuit of the relay 131 at armature 144, disconnects ground from the winding of the relay 130 at armature 143 and at armature 145 opens the locking circuit of the relay 130. The relay 132, upon operating, extends the trunk conductors 148 to 150, inclusive, to the bank contacts 125 to 127, inclusive, of the line switch C at armatures 139 and 183, opens another point in the circuit of the relay 130 at armature 141, and disconnects the first selector trunk from the banks of the finder switch S and other similar finders to which it is multiplied at armatures 139, 140, 182 and 183.

The common equipment including the finder switch F and the common repeating and line equalizing equipment J is now released and rendered available for use by another calling line. The release of the common line equalizing and receiving equipment removes the resistance that has been inserted in the circuit of the calling line so that the line characteristics are identically the same as they are in exchanges and systems of the present type.

The calling subscriber at sub-station A is supplied with battery for his telephone from the windings of the relay 403 of the repeater R.

We shall now return to the description of the operation of the connector H when connection is made with the line of the sub-station A¹. It will be recalled that there is a ringing circuit completed upon the energization of the relay 507. This ringing circuit extends from the conductor 590 which leads to the ringing interrupter equipment R I, of any usual or well known type, back contact and armature 535, armature 549 and its front contact, wiper 558, bank contact 568, conductor 590 of the called line, switch hook springs, condenser and ringer, conductor 591, bank contact 565, wiper 555, front contact and armature 542, armature 530 and its back contact and upper winding of the ring cut off relay 504 to ground. The ring cut off relay 504 is not energized over this circuit as it is constructed so as to remain unresponsive to alternating current.

The application of ground to the test wiper 553 by the operation of the armature 543 serves to busy the calling subscriber's line in the usual manner.

When the subscriber at sub-station A¹ answers there is a path for direct current provided over the above traced ringing circuit by which the relay 504 is energized to establish a locking circuit for itself at armature 531, to open one point in the ringing circuit at armature 530, to establish a point in the talking circuit at the front contact of this armature, to open a point in the circuit of the relay 506 at armature 532, to make another ground con-

nection to the relay 500 at armature 533 and to complete another point in the talking circuit at armature 535. The back bridge relay 505 is now energized over the called line loop and serves to supply talking battery to the called line. One of the results of the operation of the relay 505 is that at armature 536 the circuit by which the relay 505 supplies a busy tone to the calling line is opened.

10 The connection is now complete between the sub-station A and the sub-station A¹, the circuit over which the conversation may be carried on is indicated by the heavy conductors shown in the drawing.

15 When the conversation is terminated the release in the established connection is under control of the subscriber at sub-station A. When the subscriber at sub-station replaces his receiver upon the switch hook the circuit

20 of the relay 403 in the repeater R is opened, and this relay is immediately deenergized. The deenergization of the relay 403 brings about the release of the equipment in the repeater R, the equipment in the trunk circuit 25 G and the release of the line switch C in the same manner as has already been described.

The energization of the relay 403 in the repeater R also opens the bridge across the trunk conductors 450 and 451 and in addition 30 completes a circuit for the release magnet 407. The release magnet 407 operates to restore the wipers 433 and 434 of minor switch M¹ to normal. The opening of the bridge across the trunk conductors brings about the deenergization of the relay 501 in the connector H. The relay 501, upon deenergizing, brings about the release of the connector H of the selector S¹ in the same manner as has already 35 been described.

40 Having described the usual operation of the equipment in establishing a connection with a called line and thereafter its release, a description of certain special releasing operations which are different from those de- 45 scribed will now be considered.

When the connector H is first seized and the calling subscriber desired to release the connection the replacement of the receiver at the calling sub-station brings about the release of the connection in the same manner as has been described when the calling subscriber brought about the release responsive to the busy indication of the called line.

Should the calling subscriber hang up while 55 the vertical movement of the connector H is taking place the relay 501 is deenergized to bring about the release in the same manner as described responsive to the opening of the loop circuit in the repeater R by the deenergization of the relay 403 which occurs in response to the deenergization of the relay 205 60 in the common repeating equipment J.

From the above it will be seen that the 65 equipments may be released at any time under the control of the subscriber at sub-station A

by merely replacing the receiver up on the switch hook. It will be also be noted that the release is accomplished very quickly since there are no slow acting relays employed at any point in the circuit.

Attention is also directed to the fact that the release is brought about by opening the calling line circuit, whereas the establishing of the connection occurs by a change in an electrical characteristic of the calling line. 70 In view of this no preliminary impulses can be set. It is to be pointed out that since the desired connection is obtained by controlling the central office switching mechanism by a change in an electrical characteristic in the 75 calling line, which is measured by a current balancing circuit, in this case a Wheatstone bridge, the control of the switching mechanism is very positive.

In addition since the switching mechanism 80 at the central office including the first selectors and such other selectors as are necessary, repeaters and connectors are all operated by a local impulsive circuit, the equipment will operate to establish the connection in a fraction of the time necessary in prior systems using impulsive for controlling the switching mechanism. The switching equipment responds to impulses sent out from the calling device of the calling line at the rate of 85 about ten impulses per second. Moving under a local controlling circuit the switch can operate anywhere from 40 to 80 steps per second, that is, from 4 to 8 times as fast. Since 90 this method of control permits a much faster 95 movement of the switch it is possible to design the switching equipment to operate a great deal faster than the equipment of the present design, since the present equipment must respond to impulses sent out from the 100 calling dial.

It will be appreciated that because of the speed of the switching equipment that the amount of apparatus necessary to properly 105 establish the connection may be reduced since 110 a smaller amount of equipment may do the same amount of work by reason of its speed.

The common repeating and controlling mechanism is used solely during the establishment of the connection and since this occurs very rapidly, is rendered free and available for use in a minimum of time. Therefore, a very small number of these common equalizing and repeating equipments are necessary.

Inasmuch as means are provided for bringing the electrical characteristics of all lines to standard value by the operation of a common mechanism in the exchange, the equipment that is controlled will function with great accuracy since the change in the electrical characteristics of the line under the control of the calling device is identical with respect to all lines. The various controlling re- 125 130

lays of the selecting devices do not have to be margined to work within certain limits.

It is also to be noted that the common repeating mechanism provides means for positively controlling the operation of the selecting mechanism at all stations, and that the condition in the common repeating mechanism is maintained until a check back is received showing the completion of the operation of the desired switch.

It will be appreciated that the usual trunking arrangement employed in automatic telephone exchange systems renders as many of the switches as possible in each exchange available for common use. That is to say, the connector switches such as H will be available and may be selected by the incoming selector such as S¹, as well as the local second selectors. In order that this plan may be efficiently carried out so that the switching equipment such as the connectors or other selectors, if they are used, may be properly controlled, it is desirable that the controlling circuit in the common receiving equipment such as J in the different exchanges have sufficient resistance normally in the controlling circuit extending to the next switch to compensate for the resistance of the trunk leading into the exchange. This is not always desirable for the reason that the distance between the exchanges varies and in some cases there may be a great difference between the inter exchange trunks of a nearby exchange and the inter exchange trunks of a distant exchange. Of course, this can be compensated for by introducing resistances into the circuit of the common repeating equipment such as J. This manner of solving the problem is quite satisfactory and will overcome all possible difficulties.

In addition to the foregoing the problem set forth may be solved in a very simple manner by introducing equalizing and controlling equipment such as J, shown in Fig. 2, that is adapted to be associated with the incoming trunk lines from other exchanges. The finder switch, such as S associated with this equalizing and repeating equipment may be started by a line relay in the trunk circuit in any desired or well known manner to associate this equalizing and controlling equipment with the trunk when it is used for a call. Under these conditions the resistance of the trunks can be disregarded in the same manner and for the same reasons that the resistance of the calling lines are disregarded when common equalizing and repeating equipment such as J is employed. This last method of meeting the problem is preferable to the first one, though both will work satisfactorily.

It will be noted that common switching mechanism also allows additional time, if such is necessary, for the operation of the calling device or switching mechanisms.

The Wheatstone bridge method of control of the central office switching mechanism is very accurate since the bridge will not balance until the switching mechanism is properly positioned and since the switching mechanism controls the balancing of the bridge there is no possibility of failure.

It will be observed that the common switching equipment is connected to the first selector trunk as soon as it is seized by a calling line whereupon the balancing equipment operates to balance the line, that is, to ascertain the electrical characteristics of the line connected to it, and to then change the electrical characteristic of the line connected to it to a common standard for all lines in the exchange.

It will be appreciated that while I have described my Wheatstone bridge control circuit operating upon a change in conductance in the third and fourth legs of the bridge to control the selecting equipment, that the Wheatstone bridge circuit is particularly adapted to work upon a difference in potential as well as a difference in current. This difference of potential may be employed to secure control of the selecting devices in the telephone exchange in the same manner as described. In this case the resistors such as 106 in the various calling devices such as D can have large values

and the steps or connections to the resistor from the bank contacts can be arranged to introduce relatively large amounts of resistance into the circuit. These connections will be made so that each step of the calling device will cause the same relative voltage drop in the third or controlling leg of the bridge. Under these conditions the current flow in the third leg of the bridge can be quite small, of course, sufficient current flow must be maintained over the third leg of the bridge to maintain the quick acting release relays energized so that they may perform their usual functions. When this potential style of arrangement is employed the various other resistors in the switching equipment will be changed to correspond to the change in the resistors, such as 106, of the calling devices. With these revisions the system will work in the same manner as just described, the switching equipment being controlled by the potential drop and the balancing of potentials in the third and fourth legs of the bridge.

It will be understood that the common balancing and repeating equipment such as J which is associated with the first selector trunk when the subscriber at a calling substation removes his receiver and is released after the connection has been established, may be part of a translator or director circuit. As is well known, a director is employed in many automatic telephone systems of the present day in order to secure greater trunking efficiency and also to properly determine the route of the call in the event that there

is conflict between the first two digits of the office name. The manner in which the common repeating and balancing equipment can be converted and enlarged to perform the usual director functions will be readily apparent to those skilled in the art.

Although I have shown one particular embodiment of my invention, I am aware that many changes, modifications and deviations may be employed, and it will be understood that I desire to protect by Letters Patent all such modifications, changes, variations and deviations that come within the scope of the appended claims.

15 I claim:

1. The method of controlling a selecting device having access to a plurality of lines from a line which comprises bringing the resistance of the line to a predetermined value, varying the line resistance through definite steps from that value, comparing the line resistance as varied with a predetermined value, and governing the operation of the selecting device solely by said comparison to 25 select one of said lines.

2. In a selecting system, the combination with a circuit, a selecting device having a primary and secondary movement, and means for connecting said circuit to said device, of 30 automatic means for altering the resistance of said circuit to bring it to a predetermined value, and means for varying the resistance of said circuit to thereby control said device during its primary movement and prepare 35 its secondary movement.

3. In a selecting system, the combination with a line, a selecting device, and means for connecting said line to said selecting device, of a controlling device, means for connecting 40 said controlling device to said line, means for altering the resistance of said line, means in said controlling device responsive to said alteration to bring about a selecting movement of said selecting device, means responsive to 45 the completion of the operation of said selecting device for disconnecting said controlling device from said line and means controlled from the calling line for releasing 50 said selecting device before said controlling device is disconnected.

4. In a telephone system, the combination with a telephone line, a trunk circuit extending to an automatic switch, means for connecting said trunk to said line, of a controlling device, means for connecting said controlling device to said trunk, means for varying the resistance of said line, means in said controlling device responsive to such variations for operating said switch and means 60 controlled from said line for releasing said controlling device at any point of its operation.

5. In a telephone system, calling and called telephone lines, switching mechanism for 65 establishing connections between said lines, a

controlling device, means for connecting said device to a calling one of said lines, means for altering the resistance of the line with which the controlling device is associated, means in said controlling device responsive to such alteration to control said switching mechanism to establish said connection, means operative after the connection is established for disconnecting said controlling device from said line and rendering it available for use with another one of said calling lines and means controlled from the calling line operative at any time during the establishment of the connection for releasing said switching mechanism.

6. In a telephone system, telephone lines, switching mechanism for establishing a connection between calling and called telephone lines, a controlling device for operating said switching mechanism, means for associating said device with the calling line, means for directing the operation of said controlling device by modifying to a predetermined value the resistance of the calling line loop and means for releasing said connection at 90 any point in its establishment.

7. In a telephone system, a telephone line, an automatic switch having a plurality of selecting positions, means for extending said line to said switch, means for operating said switch to select one of said trunk lines, means for altering the resistance of the calling line, and a relay having a single winding operative responsive to said alteration in electrical characteristic of said line to control the operation of said switch.

In witness whereof, I hereunto subscribed my name this 12th day of July, 1927.

JOHN E. GARDNER.
